UNITED STATES PATENT OFFICE.

CHARLES L. WAGANDT, OF BALTIMORE, MARYLAND.

DESIGN FOR A WINDOW FRAME FOR OIL-STOVE OPENINGS.

Application filed June 26, 1922. Serial No. 2,833. Term of patent 3½ years.

To all whom it may concern:

Be it known that I, CHARLES L. WAGANDT, a citizen of the United States, residing at Baltimore, in the State of Maryland, have invented a new, original, and ornamental Design for a Window Frame for Oil-Stove Openings, of which the following is a specification, reference being had to the accompanying drawing, forming part thereof.

In the drawing—

Fig. 1 shows the window-frame in front view and

Fig. 2 illustrates the same in top or edge view.

I claim:—

The ornamental design for a window frame for oil stove openings as shown.

In testimony whereof I affix my signature.

CHARLES L. WAGANDT.
